(57) **CLAIM**

The ornamental design for a chalkboard tin for holding chalk and a stored value card, as shown and described.

DESCRIPTION

FIG. 1 is a perspective view of a chalkboard tin for holding chalk and a stored value card;

FIG. 2 is an exploded perspective view thereof;

FIG. 3 is an unexploded front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken dashed lines (- -) showing in FIGS. 1-7 are included for the purpose of illustrating portions of the chalkboard tin for holding chalk and a stored value card that form no part of the claimed design.

The oblique shading showing in FIGS. 1-3 is included for the purpose of illustrating a contrast in appearance on the lid of chalkboard tin for holding chalk and a stored value card.
